NAILING PLATE

Walter G. Moehlenpah, Ladue, Mo., assignor to Hydro-Air Engineering, Inc., St. Louis, Mo., a corporation of Missouri

Filed Aug. 3, 1960, Ser. No. 61,618

Term of patent 14 years

(Cl. D54—9)

FIG. 1.

FIG. 2.

FIG. 3.

FIG. 5.

FIG. 4.

FIG. 1 is a top perspective view of a nailing plate embodying my new design;

FIG. 2 is a bottom plan view thereof;

FIG. 3 is an edge elevational view thereof;

FIG. 4 is a fragmentary elevational view taken from the lower right side of FIG. 2; and

FIG. 5 is a sectional view on an enlarged scale taken along the lines 5—5 of FIG. 4.

I claim:

The ornamental design for a nailing plate, substantially as shown and described.
